Inventor;

Thos. F. Hamilton

By his Attorney

Thos. E. Earle

United States Patent Office.

THOMAS F. HAMILTON, OF NEW HAVEN, CONNECTICUT.

Letters Patent No. 84,822, dated December 8, 1868.

IMPROVED IMITATION-STONE FOR BUILDING-PURPOSES.

The Schedule referred to in these Letters Patent and making part of the same.

To all whom it may concern:

Be it known that I, THOMAS F. HAMILTON, of New Haven, in the county of New Haven, and State of Connecticut, have invented a new Imitation-Stone for Building-Purposes; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view, and in

Figure 2, a sectional view of a block manufactured in accordance with my invention.

The object of this invention is to produce an article for window-sills and lintels, and for other building-purposes, having finished surfaces, and at less expense than can be done in stone, yet equally as good for all practical purposes; and

The invention consists in forming such articles from hydraulic cement and sand, enclosing a block or bar of wood, which gives strength to the material.

To enable others to construct my improvement, I will fully describe the same, as illustrated in the accompanying drawings.

I first take a block or bar of wood, A, of the required length and size for the article to be produced, that is, a

block or bar narrower and thinner, then cover the whole with hydraulic cement, prepared with sand, and place the whole in a mould of the required size and form of the article to be produced, the wood lying nearly or quite in the centre, and when the cement is hardened the block is ready for use, and may be colored by adding to the cement, in the process of mixing, the proper coloring-material, or may be painted or colored after it is finished. I prefer the former.

This invention is specially adapted to the construction of window-sills and lintels, the surfaces of which are planed, but is applicable also for other purposes.

The wood not being exposed, will last for all time, and a block thus constructed is nearly, if not quite, as strong as a block of the same dimensions of common brown-stone.

Having fully described my invention,

What I claim as new and useful, and desire to secure by Letters Patent, is—

The herein-described process for forming blocks with a wood foundation and cement covering, substantially as herein set forth.

THOS. F. HAMILTON.

Witnesses:

JOHN E. EARLE,

A. J. TIBBITS.
